CLAIM

The ornamental design for a canopy light fixture with back-up battery housing, as shown and described.

DESCRIPTION

FIG. 1 is a bottom, front perspective view of a canopy light fixture with back-up battery housing;

FIG. 2 is a bottom, rear perspective view thereof;

FIG. 3 is a top, front perspective view thereof;

FIG. 4 is a top, rear perspective view thereof;

FIG. 5 is a front elevational view thereof;

FIG. 6 is a left side elevational view thereof;

FIG. 7 is a right side elevational view thereof;

FIG. 8 is a rear elevational view thereof;

FIG. 9 is a top plan view thereof; and,

FIG. 10 is a bottom plan view thereof.

The broken lines represent elements which form no part of the claimed design.
